THREAD GUIDE FOR THREAD HOLDERS

Elliot A. Santon, Worcester, Mass., assignor to
 Crompton & Knowles Loom Works, Worcester,
 Mass., a corporation of Massachusetts

Original application April 1, 1944, Serial No.
 529,147. Divided and this application July 22,
 1944, Serial No. 546,167

11 Claims. (Cl. 139—247)

This is a division of my co-pending application Serial No. 529,147, filed April 1, 1944.

This invention relates to improvements in thread holders for weft replenishing looms and it is the general object of the invention to improve the type of a thread holder having thread engaging gears.

A type of weft replenishing loom which has gone into extensive use employs several stacks of reserve bobbins arranged in a magazine. Weft ends extend from the bobbins to a holder the purpose of which is to keep the threads taut and also hold the thread of a transferred bobbin to facilitate partial threading of the shuttle on the first pick after transfer. A well-known type of thread holder employs a pair of geared members between which the weft ends pass, provision being made to cause the geared members to turn during loom operation, preferably by a vibration motor. When coarse yarns are used the weft ends form such a large bundle that the vibration motor cannot turn the geared members, and it is an important object of my present invention to provide an electric motor connected to one of the geared members and causing the latter to turn slowly during loom operation. The motor is preferably of the self-starting low speed synchronous type, although I do not wish to be limited to this particular kind of motor in the practice of my invention.

The aforesaid geared members are mounted on a support so that their axes are substantially parallel to the lay and the weft ends are led over the support and then passed downwardly to be subjected to tension by said members. The turning of the gears tends to group all the weft ends in a small area the effect of which is to impose a considerable load on the gear driving mechanism. It is another object of my present invention to provide separator means so constructed that the weft ends can be divided into groups which engage the gears at points spaced along the length of the gears. In this way the threads are distributed between the gears and do not form a sufficiently large bundle at any one point to interfere with the operation of a gear turning mechanism. The separator means is preferably arranged above the gears and is so constructed that one group of weft ends from the rear part of the magazine is directed downwardly toward the gears along a path spaced from the path traversed by the group of weft ends from the front part of the magazine.

In the weaving of certain fabrics it is customary to use two different types of yarns, such as

rayon and coarse cotton. In the reclamation of the waste threads it has been found difficult to separate these two types of yarns because of the form of thread holders heretofore used. It is a further object of my present invention to provide thread guide means below the gears defining different paths, one for each type of yarn. Thus, the guide may be constructed so that rayon yarns coming from the front of the magazine are led over a guide which directs them forwardly, while the heavy cotton yarns are led over a second guide which directs them rearwardly. The two types of weft are therefore kept separate and the labor of reclaiming the waste yarns is simplified.

While I show hereinafter guides both above and below the thread tensioning gears, yet it is to be understood that these guides need not necessarily be used together. If all the yarns are of the same kind and are large, the separator above the gears will suffice, but if two distinctive wefts are used the guide below the gears can be used either with or without the guide above the gears.

With these and other objects in view which will appear as the description proceeds, my invention resides in the combination and arrangement of parts hereinafter described and set forth.

In the accompanying drawings, wherein a convenient embodiment of my invention is set forth:

Fig. 1 is a front elevation of a portion of a weft replenishing loom having my invention applied thereto,

Fig. 2 is a side elevation looking in the direction of arrow 2, Fig. 1,

Fig. 3 is an enlarged side elevation looking in the direction of arrow 3, Fig. 1, showing both the top and bottom separators or guides for the weft ends,

Fig. 4 is a horizontal section on line 4—4, Fig. 3, showing the driving motor for one of the gears,

Fig. 5 is an enlarged side elevation showing the interior of the casing on which the thread gears are mounted as seen from the center of the loom, with the dust protector plate removed, and looking in the direction of arrow 5, Fig. 1,

Fig. 6 is an enlarged detail plan, partly in section, of the connection between the driving motor and one of the thread gears,

Fig. 7 is a front elevation of the thread holder looking in the direction of arrow 7, Fig. 3,

Fig. 8 is a plan view of the thread holder looking in the direction of arrow 7, Fig. 3,

Fig. 9 is a diagrammatic view showing the electric control circuit for the motor.

Referring particularly to Figs. 1 and 2, I have shown a loom frame 10, a lay 11, and picking mechanism 12 to actuate a shuttle S. Looms of the type to which my invention is more particularly applicable ordinarily operate with several shuttles each of which in its turn occupies the position shown in Fig. 1 under magazine M for replenishment. The magazine is provided with bobbins B arranged in front and back pairs of stacks from which extend weft end groups G' and G2, respectively. These groups of threads extend to a thread holder designated generally at H mounted on an arm 13 secured at 14 to some part of the magazine, such as a tie rod 15.

The thread holder is provided with front and back thread engaging gears 20 and 21, respectively, mounted on a casing 22 having a side wall 23, end walls 24 and 25 and top and bottom walls 26. Thread gear 21 is secured to shaft 27 which turns in a bearing 28 on the upper end of an arm 29 pivoted on a stud 30 secured to the casing. A light coil spring 31 lies between arm 29 and a flat spring 32 the upper end of which is secured as at 33 to one wall 25. An adjusting screw 34 threaded into wall 25 adjacent to the flat spring engages the lower end of the latter to adjust the same toward and from arm 29 for the purpose of varying the force exerted by spring 31. Spring 31 is weaker than the flat spring and will be compressed when the latter is moved to the dotted line position shown in Fig. 5 to increase resistance to pivotal movement of the gear 21 in a rearward direction, or to the right as viewed in Fig. 3.

The front geared member 20 is secured to a shaft 40 which turns in a bearing 41 fixed with respect to the thread holder casing. A small electric motor E is mounted on tubular supports 42 and held in position by screws 43 passing through the supports and tapped into the vertical side wall 23. A coupling 44, see Fig. 6, connects shaft 41 with the shaft 45 of the motor. The motor is located within casing 22 and is protected by the usual cover 46.

The motor is supplied with electric power by two insulated wires 47 and 48 which, as shown in Fig. 5, lead from the motor out of the bottom wall 26 and then along the latter to be attached for supporting purposes as at 49 to the arm 13. The wires 47 and 48 then extend along arm 13 to a transformer box 50 which supplies electric energy for turning the motor.

As shown in Fig. 9 the circuit containing the motor E is under control of some part of the loom which determines whether the loom shall run or be stopped. There are two general ways of stopping the loom, one through the shipper mechanism, and the other by stopping the driving motor, but I do not deem it necessary to show controls exercised by both of these stopping methods. I have shown, however, means by which stopping of the loom through the shipper handle will effect stoppage of the motor E.

Referring to Fig. 9 the shipper handle 52 when in the forward running position, that is to the left, Figs. 2 and 9, effects closure of a switch 53, but when the shipper handle moves rearwardly, or to the dotted line position shown in Fig. 9, the switch 53 is open. The circuit shown in Fig. 9 indicates how the shipper mechanism controls the motor E. When the shipper handle is in running position current will flow in the following circuit: secondary 55 of the transformer T, wire 56 to

switch 53, wire 57, wire 47, the motor E, and wire 48 back to the other side of the secondary winding 55. So long as the shipper handle is in running position this circuit is closed and the motor E continues to run at a very slow rate, such as four to eight revolutions per minute. When the shipper handle is moved to stopping position, however, the switch 53 is opened, and the circuit is broken, stopping the motor. By this control the thread holder motor E runs only during loom operation.

If the yarns of both groups of threads G' and G2 were large they would impose too heavy a load on the gears 20 and 21 if the thread holder were made substantially as constructed heretofore. In order to distribute the load I provide a separator 60 which as shown in Fig. 7 has a vertical wall 61 secured by screws 62 to the thread holder casing. This wall extends upwardly and then extends horizontally as at 63 over the top wall 26 of the casing. The left part of the separator projects over gear 20 as at 64 to a point substantially midway of the length thereof as shown in Fig. 7. A side edge 65 on part 64 leads to the right, Fig. 8, to an upstanding horn 66 which may be in the form of a hook to limit rearward movement of weft threads. The rear part of the guide 60 is cut away as at 67 to expose the rear thread gear 21. The thread holder casing 22 has the usual guide 68 which overhangs a part of both of the gears 20 and 21. This guide 68 has a thread engaging edge 69 which is nearer the magazine than is thread guiding edge 65.

In using the separator 60, the group of yarns 62 from the back of the magazine will be led over the separator 60 and permitted to fall over the edge 69 and onto gear 21. The gears are then spun manually and group G2 is drawn downwardly between the gears 20 and 21 to a position designated at A close to guide 68. The second group of threads G' from the front of the magazine is then led over edge 65 and allowed to fall on gear 20. This group G' will eventually occupy the position designated at B between the gears and spaced outwardly from guide 68. The bundles of threads at positions A and B are spaced from each other so that the load on the motor E will be much less than would be the case if all the threads should occupy the position which they would take under former construction, that is, at A.

If groups G' and G2 are formed of different types of yarn, such as rayon and coarse cotton it is desirable that they be separated below the gears to simplify reclamation. Accordingly, I provide means below the gears defining two different paths leading away from said gears, one of said paths extending forwardly for one type of yarn and the other path leading rearwardly for the other type of yarn. In Figs. 3 and 7 I have shown a thread guide or separator 70 made with oppositely extending ears 71 and 72 held to wall 23 by screws 73. The intermediate part of guide 70 is made with upwardly converging floors 75 and 76 formed with side flanges 77 and 78, respectively. The floors and flanges form front and back guide troughs 80 and 81, respectively, which extend, as indicated in Fig. 7, to positions under the thread guide 68 to hold the threads in proper position.

When using the guide or separator 70, the front group of threads G' will be led downwardly between the gears 20 and 21 and then moved forwardly into the front trough 80, and then the rear group G2 after being passed between the gears, will be directed along the rear trough 81.

The two groups are therefore kept separate and can be gathered independently of each other for reclamation purposes. It is obvious that under certain conditions it will be sufficient if only one of the guide troughs is used, since one of them will deflect its group away from the center of the thread holder and the other group can hang as usual below the line of mesh of the gears 20 and 21. It is apparent also that I am not limited to the particular form of guide 70, since it is sufficient if a thread guide is used which is spaced from a vertical line passing through the line of mesh of the gears and over which one of the groups may be trained.

The upper guide 60 and lower guide 70 can be used together when two types of weft are being woven, but it may not always be necessary to use the top guide 60 with two types of weft, since the fine yarns add very little to the total size of the bundle of weft ends and all of the latter can hang down over the edge 69 as heretofore and be separated by the guide 70. In similar manner, top guide 60 can be used without the bottom guide 70 when all the yarns are of the same type.

From the foregoing it will be seen that I have provided simple means for driving the thread gears 20 and 21 continuously during loom operation by means of a small electric motor which can be housed in the usual type of casing heretofore provided for geared thread holders. It will also be seen that the motor for the gears is controlled so that it will run only when needed. Further, it will be noted that I have provided a thread separator 60 overhanging the thread gears and effective to separate the yarns into two groups which engage the gears at different points along their lengths. The top separator 60 can of course be used with both light and coarse yarns if desired. Furthermore, it will be seen that I have provided a thread guide 70 below the gears 20 and 21 to separate the bundles of weft ends when two types of weft are used in the loom, the purpose of the separation being to simplify reclaiming of the waste threads.

Having thus described my invention it will be seen that changes and modifications may be made therein by those skilled in the art without departing from the spirit and scope of the invention and I do not wish to be limited to the details herein disclosed, but what I claim is:

1. In a weft replenishing mechanism away from which extend two groups of weft threads, a pair of meshing geared members rotating to draw the threads away from said mechanism and having axes extending toward the latter, and two guides extending above said members at different distances from said mechanism, one of said guides engaging and guiding one of said groups toward said members along a path relatively near said mechanism and the other guide engaging and guiding the other group toward said members along a path farther from said mechanism.

2. In a weft replenishing mechanism away from which extend two groups of weft threads, a pair of meshing geared members rotating to draw the threads away from said mechanism and having axes extending toward the latter, two guides extending above said members at different distances from said mechanism, one of said guides engaging and guiding one of said groups toward said members along a path relatively near said mechanism and the other guide engaging and guiding the other group toward said members along a path farther from said mechanism, and means on said other guide limiting movement of

said other group in one direction relatively to said other guide.

3. In a weft replenishing mechanism away from which extend two groups of weft threads, a pair of meshing geared members rotating to draw the threads away from said mechanism and having axes extending toward the latter, two guides extending above said members at different distances from said mechanism, one of said guides engaging and guiding one of said groups toward said members along a path relatively near said mechanism and the other guide engaging and guiding the other group toward said members along a path farther from said mechanism, and means on said other guide extending away from said geared members and limiting movement of said other group in one direction relatively to said other guide.

4. In a weft replenishing mechanism away from which extend two groups of weft threads, a pair of meshing geared members rotating to draw the threads away from said mechanism and having axes extending toward the latter, and two guides above said geared members at different distances from said mechanism, one guide for each group of threads, and each guide directing the group corresponding thereto toward said members along a path spaced from the path of the other group.

5. In a weft replenishing mechanism away from which two groups of threads are drawn by rotating geared members having teeth between which said threads extend, a guide overhanging one of said members and directing one of said groups of threads toward said members along a path at a given distance from said mechanism, and a second guide overhanging the other of said members and directing the other group of threads toward said members along a path at a distance from said mechanism greater than said given distance, the teeth of each geared member extending beyond the corresponding guide in a direction away from said mechanism.

6. In a thread holder for a weft replenishing mechanism having two types of weft ends extending therefrom and drawn downwardly between rotating geared members which deliver said weft ends downwardly, guide means below said geared members defining two different paths for said weft ends, one path for each of said types of weft ends.

7. In a thread holder for a weft replenishing mechanism having two types of weft ends extending therefrom and drawn downwardly between rotating geared members which deliver said weft ends downwardly, a support on which said geared members are rotatably mounted, and means secured to said support below said members defining two guide troughs for said weft ends, one trough for each of said types of weft ends.

8. In a thread holder for a weft replenishing mechanism having two types of weft ends extending therefrom and drawn downwardly between rotating geared members which deliver said weft ends downwardly, a support on which said geared members are rotatably mounted, and a thread guide on said support below said members and located to one side of a vertical line passing centrally between the axes of said members to hold one of said groups spaced from the other group.

9. In a thread holder for a weft replenishing mechanism having two types of weft ends extending therefrom and drawn downwardly between rotating geared members which deliver said weft ends downwardly, a support on which said geared

members are rotatably mounted, and a pair of thread guides on said support spaced horizontally and lying on opposite sides of a vertical line passing centrally between the axes of said members, one guide for each of said two types of weft ends, each guide causing the corresponding type of weft ends to follow a path directed away from the path of the other type of weft ends.

10. In a thread holder having a support for a pair of thread tensioning members, a carrier pivoted on said support and mounting one of said members for movement toward and from the other member, a flat spring one end of which is secured to said support, resilient means between said spring and said carrier exerting a force on the latter tending to move said one member toward said other member, and adjusting means to change the position of the other end of said flat

spring relatively to said carrier to vary the force exerted by said resilient means on said carrier.

11. In a thread holder having a support for a pair of thread tensioning members, a carrier pivoted on said support and mounting one of said members for movement toward and from the other member, a flat spring one end of which is secured to said support, a coiled compression spring between the ends of said flat spring and said carrier exerting a force on said carrier tending to move said one member toward the other member, and an adjusting screw on said support engaging the other end of said flat spring to change the position of the latter relatively to said support in a direction toward and from said carrier to vary the force exerted by said coiled spring on said carrier.

ELLIOT A. SANTON.
